UNITED STATES PATENT OFFICE.

LEW YEN, OF SAN FRANCISCO, CALIFORNIA.

DESIGN FOR A BASKET.

60,119.

Specification for Design.

Patented Dec. 27, 1921.

Application filed October 16, 1920. Serial No. 417,495. Term of patent 7 years.

To all whom it may concern:

Be it known that I, LEW YEN, a citizen of the Republic of China, residing in the city and county of San Francisco and State of California, have invented a new, original, and ornamental Design for a Basket, of which the following is a specification, reference being had to the accompanying drawing, forming part thereof.

The figure is a perspective view of a basket showing my new design.

I claim:

The ornamental design for a basket, as shown.

LEW YEN.
